UNITED STATES PATENT OFFICE.

SAM SORENSEN, OF HOUSTON, TEXAS.

LIFTING JACK.

Application filed September 8, 1922. Serial No. 586,977.

To all whom it may concern:

Be it known that I, SAM SORENSEN, a citizen of the United States, residing at Houston, Harris County, Texas, have invented a certain new and useful Improvement in Lifting Jacks, of which the following is a full, clear, and exact description, such as will enable others skilled in the art to which it appertains to make and use the same.

10 My invention relates to lifting jacks of the portable type. It is particularly adapted for ordinary use in lifting of motor vehicles, or similar loads.

15 The object of my invention is to provide a lifting jack which may be quickly and easily operated and that will not require a latch of any kind to retain it in adjusted position.

20 It is also desired to construct a jack which will be simple and strong, and hence not liable to break or get out of order.

These and other objects and advantages will more clearly appear from the description which follows. Referring to the drawings wherein like numerals of reference are applied to like parts in all the views, Fig. 1 is a front elevation with a part of the housing broken away for greater clearness. 25 Fig. 2 is a side elevation partly in broken vertical section. Fig. 3 is a detail of the rack, and Fig. 4 illustrates the rack-engaging pinion.

30 In the construction of my device I have a vertically slideable lifting portion 1, having teeth 2 formed on the two opposite sides, thus providing a rack. The upper end of this lifting rack terminates in a head 3 formed of a rectangular plate as shown.

35 The rack 1 is mounted within a supporting housing comprising a back plate 6 formed with forwardly extending marginal flanges 5. Spaced forwardly from the plate 6 and about midway of the upper end of the housing, and fitting over the forward face of the lower portion thereof, is a second plate 7. This plate is wider at its upper end to fit within the housing 5, and is narrowed at its lower end, and is secured to the 40 forward portion of the housing by means of bolts 8 or other similar means.

45 Immediately in front of the plate 7 I form a chamber 9 within which is housed a series of gears. At the upper portion of the housing are two intermeshed gears, 10 and 11. These gears are mounted upon sim-

ilar shafts 12. The gears 10 and 11 are fixed upon the shafts 12 and the said shafts are extended through the plate 7 and the housing 4 to form a bearing therein. The 60 shafts are so positioned as to project through plate 7 and to fit within the semi-cylindrical recesses 14 between the adjacent teeth of the rack 1. The recesses 14 are approximately semi-cylindrical, yet 65 somewhat elongated so as to allow a slight space at either side of the shaft 12 fitted therein. As shown particularly in Fig. 4, the shaft 12 is hollowed out centrally into tubular shape, and one side thereof is cut 70 away so as to leave a crescent shaped portion 15 to fit against the rack 1.

75 There are also two lower gears 10' and 11' exactly similar in construction to the two upper gears, and the shafts 12 upon 80 which they are mounted are also formed into pinions 16 adapted to cooperate with the teeth of the rack 2. As will be noted in Fig. 3 the position of the pinions relative to the rack, are reversed in the lower shafts 85 over that of the upper shaft, so that while the upper pinions are turned into the convex side of the crescent fitting within the notch or recess 14 between the adjacent teeth, the lower pinions are contacting with 90 the teeth of the rack with the concave side of the pinion.

95 The two sets of pinions are operated through the gears 10, 10', 11 and 11' by means of an operating gear 17, mounted in the housing midway between the upper and lower sets of gears and meshing with those on one side of the housing only. The gear 17 is mounted upon an operating shaft 18 which is supported at its inner end within the plate 7 and on the outer portion thereof within the plate 19, which acts as a cover plate for the forward face of the upper portion of the housing. The gear 17 is mounted rigidly thereon midway between the plates 100 7 and 19, and is thereby housed and protected against dust and dirt. The rotation of the shaft 18 in either direction will cause the simultaneous rotation of the two gears 10 and 10', and by that means will also rotate the two gears 11 and 11'. It will be noted that by this arrangement the two gears 10 and 10' will be rotated in the same direction and the two gears 11 and 11' will 105 be rotated in the same direction, but in the opposite direction from the gears 10 and 10'.

If desired, a universal joint 20 may be formed on the shaft 18 and a crank 21 secured to said joint so that the rotation of the crank 21 will thereby rotate the shaft 18, and adjustment in the position of the crank 21 may be made to accommodate different positions of the jack during operation. By this means the tool may be placed in otherwise difficult positions and still operate readily. The upper plate 3 which is adapted to contact with the work is made almost square and may be therefore placed in position at almost any desired angle and work equally well in all positions.

In the operation of my device the jack is placed in position beneath the axle of the car, or any other desired load to be lifted, and when thus in position the turning of the crank 21 will cause the rotation of the different gears, in the manner described. With special reference to Fig. 3 it will be noted that the rotation of the shafts 12 will cause the pinions 16 thereon to alternately engage the teeth on the rack 1 as shown at the lower end of the said figure, and to raise or lower the said rack according to the direction of rotation of the crank. The upper pinions will be in the opposite position with the convex side fitting within the recesses 14. It will therefore be apparent that as the gears are rotated the rack will be raised or lowered in the desired direction, and when the load has been raised to the desired point the load will be sustained in that position automatically through the pinions 16. In the position shown in Fig. 3 the upper pinions will be in supporting position and will automatically retain the rack in that position. There will be no tendency of the weight or load upon the rack to cause the rotation of the pinions 16 due to the shape thereof. It will therefore be observed that the load may be very readily raised and lowered, and the action of the tool may be stopped at any desired point, and will automatically maintain itself in adjusted position. When it is desired to release the load, the rotation of the crank in the opposite direction will immediately cause the movement of the supporting rack in the opposite direction and lower the load and release the jack. The advantages of this tool will be apparent to one skilled in the art without further description.

What I claim as new and desire to protect by Letters Patent is:

1. In a lifting jack, a supporting housing, a rack slidable vertically therein, teeth on each side of said rack shaped to provide approximately semicylindrical recesses between adjacent teeth, a pinion formed

with a crescent-shaped portion adapted to fit on its outer side within each said recesses and when rotated to engage said teeth on its opposite side, and means to rotate said pinion.

2. In a lifting jack, a supporting housing, a rack slidable vertically therein, teeth on two sides of said rack having approximately semicircular recesses between adjacent teeth, pinions having crescent-shaped portions coacting with said rack to raise or lower the same when said pinions are rotated, gears on said pinions, and means to operate said gears.

3. In a lifting jack, a supporting housing, a longitudinally slidable rack in said housing, teeth on opposite sides of said rack, a plurality of sets of opposite crescent-shaped pinions shaped to fit between said teeth on their convex sides and to engage said teeth with their concave sides when rotated, said sets of pinions arranged so that when one set presents its concave portion to the rack, another set will present its convex portion to the rack, and means to rotate said pinions simultaneously.

4. In a lifting jack, a supporting housing, a vertically slidable, lifting rack in said housing, teeth on one side of said rack having approximately semicylindrical recesses between them, upper and lower crescent-shaped pinions shaped to fit loosely within said recesses on their convex sides, and to engage said teeth with their concave sides when rotated, the upper pinion being arranged to engage said teeth when the lower pinion is disengaged and means to rotate said pinions simultaneously in the same direction.

5. In a lifting jack, the combination of a supporting housing, a lifting rack slidable therein and having teeth thereon, upper and lower lifting elements engaging said teeth and adapted in one position to support said rack and when rotated from said position to engage said teeth to move said rack, and means to rotate said elements, one element being in supporting position when the other is in lifting position.

6. In a jack, a lifting rack, a support therefor, teeth on said rack, crescent-shaped pinions engaging said rack, and means to rotate said pinions simultaneously in the same direction, said pinions being adapted to support said rack when the convex side of the pinion engages the rack, one or the other of said pinions being in supporting position at all times.

In testimony whereof, I hereunto affixed my signature, this the 2nd day of September, A. D. 1922.

SAM SORENSEN.
